(57) **CLAIM**

The ornamental design for a pet footwear configured to hold a GPS tracker as shown and described.

DESCRIPTION

FIG. 1 is a top front perspective view of a pet footwear configured to hold a GPS tracker showing my new design; FIG. 2 is a bottom rear perspective view thereof;

FIG. 3 is a front view thereof;

FIG. 4 is a rear view thereof;

FIG. 5 is left side view thereof;

FIG. 6 is a top view thereof; and,

FIG. 7 is a bottom view thereof.

A right side view has been omitted, as it is a mirror image of the left side view of FIG. 5 and is also claimed.

The broken lines in the drawings depict portions of the pet footwear configured to hold a GPS tracker that form no part of the claimed design.
